GAME BALL LIFTER

Filed July 9, 1925

UNITED STATES PATENT OFFICE.

ROBERT A. WILSON, OF DALLAS, TEXAS.

GAME-BALL LIFTER.

Application filed July 9, 1925. Serial No. 42,381.

This invention relates to new and useful improvements in game ball lifters.

In playing such games as golf the players put the ball into a cup at the center of the green and after all the players have succeeded in putting the balls into the cups, it is necessary to reach into the cup and remove the balls.

The object of my invention is to provide in conjunction with the usual metal signal staff means for lifting the ball or balls from the cup when the staff is raised, thus obviating the necessity of stooping over and picking the balls from the cup.

15 A further object of the invention is to provide a device for preventing extraneous matter filling the cup and also for cleaning the cup when desired.

A construction designed to carry out the invention will be hereinafter described together with other features of the invention.

The invention will be more readily understood from a reading of the following specification and by reference to the accompanying drawing, in which an example of the invention is shown and wherein:—

Fig. 1 is a vertical sectional view of a golf green cup showing a lifter constructed in accordance with my invention and attached to the staff of the marker.

Fig. 2 is a plan view of the same, the marker staff being in section,

Fig. 3 is a cross-sectional view taken on the line 3—3 of Fig. 1,

35 Fig. 4 is a vertical sectional view showing a modified form, and

Fig. 5 is an enlarged detail of the stop used with the modified form.

In the drawings the numeral 10 designates 40 the usual cylindrical metal cup which may be made with or without a bottom, the former being illustrated. About midway of the cup a transverse spider 12 is secured therein. This spider has a central collar 13.

45 It is customary to designate the green or "hole" with a marker which I have shown as comprising an upright staff 14 with a suitable handle 15 at its upper end. Just below the handle a signal is secured to the staff and this signal may be a target 16 bearing the number of the green or it may be flag 17. All of the foregoing parts are in common use and form no novel feature of the invention.

55 The staff is inserted in the collar and its

lower end, which is usually pointed, is pushed into the ground at the bottom of the cup. In carrying out the invention I secure a circular apron or disk 18 on the staff in any suitable manner, as by passing 60 the staff through the center of the apron and welding said apron thereon. The apron is slightly inclined toward its outer margin and is formed with a marginal flange 19 turned up so as to form a circular groove or 65 trough contiguous to its edge. However it is to be understood that the exact manner of forming the apron, the material used and the method of mounting the apron upon the staff, is subject to variation within the scope 70 of the appended claims.

When a ball is putted into the cup it will fall upon the apron 18 which is resting upon the spider 12. Owing to the inclination of the apron the ball will roll against the 75 inner wall of the cup. If it is desired to remove the ball the handle 15 is grasped and the staff 14 is raised, whereby the apron becomes a lifter and carries the ball up the wall of the cup. When the apron emerges 80 from the rim of the cup the ball will roll against the flange 19 so as to overhang the apron above the green immediately surrounding the cup. The ball may be removed from the apron in any suitable way. 85

An invention of this nature permits of considerable variation within its scope and as a further illustration I have shown another form in Figs. 4 and 5. In this form a stop collar 20 is fastened on the staff by a 90 set screw 21 or in any other suitable manner. The collar is positioned below the collar 13 of the spider 12 at such a point that when the apron is elevated to the top of the cup, said collar 20 will strike the collar 13, 95 thus arresting the lifter suddenly which will jar the apron and dislodge the ball therefrom.

It is pointed out that the apron fits comparatively close in the cup and thus match stems, twigs, grass cuttings and obstructions lodging in the cup will fall upon the apron and will be dislodged from the cup when the apron is lifted. 100

What I claim, is:—

1. The combination with the staff of a golf green marker, the cup receiving said marker, and the spider in said cup, of an apron secured on the staff just above said spider for receiving the balls putted into 110

the cup and for lifting the same therefrom when the staff is elevated, and a stop fastened on the staff below the spider for impinging upon the spider and limiting the upward movement of the staff and apron.

5. A game ball lifter comprising a cup having a spider intermediate its ends with

a central bearing, a staff slidingly mounted in said bearing, and a cup secured upon said staff to rest upon the spider and having its body inclined radially and downwardly and terminating in an upturned flange.

10 In testimony whereof I affix my signature.

ROBERT A. WILSON.
